TRAVELLING WAVE DEVICES

John M. Osepchuk, Lexington, Mass., assignor to Raytheon Company, Lexington, Mass., a corporation of Delaware

Filed Feb. 10, 1960, Ser. No. 7,821

6 Claims. (Cl. 315—39.3)

This invention relates to travelling wave electron discharge devices and, more particularly, to methods and means of construction of an M-type backward wave oscillator having novel means to insure proper electron beam collection.

In travelling wave electron discharge devices, electrical waves travelling along a slow wave propagation structure in a tube interact with the field from electrons moving along paths adjacent said structure to produce amplification of the travelling wave. The longitudinal component of the field of the wave interacts with the field of the electrons travelling along in approximate synchronism with it. Some electrons are accelerated and others are decelerated resulting in a progressive arrangement of electrons in phase with respect to the waves. This process of mutual interaction continues along the length of the structure with the result that D.C. energy is given up by the electron beam to the wave as radio frequency energy and, thus, the wave is amplified.

In a travelling wave tube the slow wave propagation structure may be considered to consist of a number of cells in line. Since such a structure is periodic, the fields induced in adjacent cells by the propagated wave, have the same spatial distribution but differ uniformly in phase. The electron beam field interacts with the fields in the cells and this interaction is maximum when the velocity of the electrons is such that their fields encounter the fields in successive cells in the same phase. In other words, maximum interaction occurs when the electron velocity coincides with the phase velocity of RF waves propagating either in the same or in the opposite direction to the direction of RF power flow. These RF waves are called direct and reverse, respectively, depending on the direction of RF power flow. Consequently, when the beam velocity is equal to the velocity of the reverse wave, the amplitude of the fields in the cells increases towards the origin of the beam. One type of travelling wave tube, sometimes called a backward wave oscillator, produces radio frequency oscillations by the interaction of an electron beam travelling at substantially the same velocity as the reverse wave.

In one type of backward wave oscillator, sometimes called a type M carcinotron, the electron beam moves in crossed electric and magnetic fields in the interelectrode space between a wave propagation structure called the "line," and an elongated electrode parallel thereto, called the "sole." The average translational velocity of an electron in the beam is equal to the ratio of the electric field E to the magnetic field B. The variation of the oscillator frequency with line-to-sole voltage is determined by the dispersion characteristics of the beam and the average electron velocity. Therefore, frequency depends on both the electrical field and the magnetic field.

As the electron beam gives up energy to the radio frequency wave in the line, it loses potential energy, however, it maintains the same translational velocity. Since the beam electrons lose potential energy, they must move through substantially higher equi-potential lines of the electrical field E between the line and the sole. Consequently, electrons will move either towards the line or towards the sole, depending on the direction of the field E, and eventually these electrons will be captured by a collector electrode. In some applications the collector

2

is at the same potential as the line and in others it is at the same potential as the sole. If the beam is projected into the interelectrode space between the line and the sole along an equi-potential line V_0 and the potential between the line and the sole is V, the electrical efficiency of the system, η , is given by the following equation which assumes that electrons move over ideal linear trajectories:

$$\eta = 1 - V_0/V$$

- 10 The efficiency η is further modified by space charge effects and the fact that some of the electrons are captured by the line or the sole, depending on which is at the higher potential. It is generally preferred to ground the line and the collector and to vary sole potential to change E and, thereby, tune the oscillator.
- 15 Heretofore, the problem of preventing electron leakage past the collector has been met by making the distance between the collector and the sole approximately one half the distance between the line and the sole, as shown in FIG. 1. Such a design insures that substantially all of the beam electrons will be collected by the collector and substantially none will leak past the collector. Since the separation between the line and the sole is, in most applications, very small (between .100 and .010 inch), it is, obviously, difficult to construct such a device with such small separation between collector and sole. Furthermore, by placing the anode and the sole so very close, arcing is likely to occur because the potential difference between the anode and sole is usually very large (many thousands of volts). Such arcing is obviously undesirable since its immediate and ultimate effect is to introduce considerable noise in the output of the device. Therefore, it is an object of the present invention to provide a backward wave oscillator having none of the above-mentioned limitations of prior devices.

30 It is another object of the present invention to provide an electron collector in an M-type backward wave oscillator for collecting a substantial part of the electron beam therein.

40 It is another object to provide such a collector structure wherein equal electrical fields are maintained between the collector and the sole and between the line and the sole.

45 It is another object to provide a backward wave oscillator in which beam dispersion is substantially greater between the collector and the sole than between the line and the sole.

50 It is another object to provide an M-type backward wave oscillator in which the magnetic field in the interelectrode space between the collector and the sole is substantially less than the magnetic field between the line and the sole.

55 It is another object to provide a backward wave oscillator tunable by varying sole potential while at the same time maintaining the electric field adjacent to the sole uniform throughout the length of the sole.

60 It is a feature of the present invention to provide a travelling wave type electron discharge device including an elongated structure at one potential for propagating a slow wave disposed opposite a similarly elongated conductor at another potential so as to form a substantially uniform electric field in the space therebetween, to provide electron emitting means at one end of the space and electron collector means at the other end of the space, to dispose said device in a substantially uniform magnetic field and to magnetically shield a part of said space in the vicinity of said electron collector.

65 It is another feature of the present invention to provide a backward wave oscillator device including a slow wave propagating structure, a collector electrode, and a sole electrode forming an interelectrode space therebetween and an electron gun projecting electrons into said inter-

electrode space with means in the vicinity of said collector electrode for magnetically shielding electrons in that vicinity to, thereby, insure collection of electrons by the collector and to substantially diminish flow of electrons past the collector.

It is another feature to electrically couple said electron collector to the end of said wave propagating structure thereby forming one end of the interelectrode space and to dispose magnetic materials thereabout to shield that one end from the magnetic field.

It is another feature to dispose said device in the magnetic field so that the electric field, the magnetic field and the general direction of motion of electrons within the interelectrode space are mutually perpendicular and to obtain an RF output from the device at the end of the wave propagating structure nearest the electron gun.

Other features and objects of the present invention will be more apparent from the following specific description of the prior art and embodiments of the present invention taken in conjunction with the drawings in which:

FIG. 1 is a symbolic diagram showing one prior method for insuring the collection of electrons by a collector electrode in an M-type backward wave oscillator;

FIG. 2 is a symbolic diagram of an M-type backward wave oscillator incorporating features of the present invention; and

FIGS. 3 and 4 are cross sectional views of one embodiment of the present invention featuring a circular interelectrode space and suitable magnetic materials disposed about one end thereof to magnetically shield the space in the vicinity of a collector electrode.

Turning first to FIG. 1 there is shown symbolically a typical M-type carcinotron such as employed in the past demonstrating one prior method for insuring that a substantial part of the electron beam will flow to the collector electrode and not past the collector. As shown in FIG. 1 electrodes are disposed within an envelope 1 and these include a cathode 2, a slow wave structure or delay line 3, with an accelerating electrode 4 at one end, and a collector electrode 5 at the other end. The accelerating electrode 4, the structure 3 and the collector electrode 5 are frequently coupled together and substantially in line as shown in FIG. 1. Another electrode, 6, called the sole electrode having an elongated shape is disposed within the envelope 1 opposite structure 3 and collector electrode 5 to form interelectrode space 7. It is convenient to place structure 3 and electrode 5 at ground potential and to place sole electrode 6 substantially below ground potential, for example, at about minus 7 kv., by coupling to potential source 8 thereby creating electric field E_1 , in region one, running from the slow wave structure 3 to the sole 6 and electric field E_2 , in region two, running from collector 5 to sole 6. Cathode 2 is preferably placed at a potential higher than electrode 6, for example, minus 5 kv., by coupling to potential source 9. Electrons in the beam 10, emitted from cathode 2 are accelerated for entry into interelectrode space 7. This is accomplished by coupling cathode 2 and electrode 4 to potential source 10 so that accelerator electrode 4 is at the highest potential.

In operation, a substantially uniform magnetic field is applied perpendicular to the electric field and is represented in FIG. 1 by a circle with a dot in its center and denoted B. Consequently, electrons emitted from cathode 2 are first accelerated towards electrode 4 and then into space 7, moving down the length of the space at a velocity established by the electric field E_1 and the magnetic field B. The general movement of the electrons down the length of space 7 is substantially as shown by mean 10, the electrons proceeding down the length of the space and dispersing near its end for collection by the collector electrode 5.

As already mentioned in the introduction, the beam electrons moving down the length of space 7 gives up energy to the radio frequency wave propagated in the slow wave structure 3 and as the beam gives up energy it

loses potential energy while, nevertheless, the electrons will maintain their general translational velocity down the length of space 7. Since the beam electrons lose energy they must move through substantially higher potential

lines in the electrical field between the line and the sole electrode, consequently, the electrons will move toward line 3. Part of the beam under efficient interaction, therefore, is collected by the delay line, but generally there is always a substantial part of the beam entering the collector region. In order to insure almost complete collection of this latter part of the beam, it has been the practice in the past to dispose collector electrode 5 closer to the sole electrode 6 than the structure 3. In fact, it is desirable that the space denoted d_2 between collector electrode 5 and sole electrode 6 be approximately one half the spacing d_1 between structure 3 and sole 6. The purpose of this is apparent when one considers the relationship between the potential difference V_m across an interelectrode space required to insure complete beam collection by an electrode, and the dimensions d. It can be shown that this relationship is given by the following:

$$V_m = \frac{\epsilon}{2} (Bd)^2$$

In the above expression, ϵ is the charge to mass ratio of an electron, and B is the magnitude of the transverse magnetic field in the cavity. Obviously, when B is fixed, the potential difference required to insure complete collection of electrons by an electrode may be decreased by decreasing the separation d. As already mentioned, this method is employed in some applications to insure complete beam collection by a collector electrode. However, in such applications d_1 is very small and, of course, d_2 is smaller yet. Since the potential between collector electrode 5 and sole electrode 6 is many thousands of volts, arcing is likely to occur therebetween resulting in numerous undesired effects.

Turning next to FIG. 2 there is shown a symbolic representation incorporating features of the present invention whereby such problems of arcing are substantially eliminated. The structure shown in FIG. 2 is similar to the structure shown in FIG. 1 and includes an envelope 11 enclosing a slow wave propagation structure 12, accelerating electrode 13, collector electrode 14, sole electrode 15 and cathode 16 forming interelectrode space 17 with an RF output taken from one end of structure 12, denoted 18. In operation, electrode 14 and structure 12 may be electrically coupled together and placed at, for example, ground potential while sole electrode 15 is placed at, for example, minus 7 k.v. by coupling to source 19, cathode 16 is placed at minus 5 k.v. by coupling to source 20 and accelerating electrode 13 is placed at minus 3 k.v. by coupling to source 20 as shown in the figure. The device is placed in a magnetic field which is perpendicular to the electric field created within space 17 and also perpendicular to the general motion of electrons within the space represented by beam 21. Electrons emitted from cathode 16 are accelerated by accelerating electrode 13 and proceed down the length of space 17 moving to higher and higher equi-potential lines as energy is given up from the electron beam to the wave in structure 12. Magnetic shielding pieces 22 and 23 are disposed substantially contiguously with collector electrode 14 and one end of sole electrode 15, respectively, as shown in the figure. These magnetic shielding pieces may be, for example, flat in shape and orientated with their smallest dimension perpendicular to the applied magnetic field so as to afford magnetic shielding in region two of interelectrode space 17 formed by the collector electrode 14 and one end of sole electrode 15. Consequently, the magnetic field in region two of space 17 is substantially less than the magnetic field in region one. If the magnetic field in region one is denoted B_1 and the magnetic field in region two is denoted B_2 , then the expression for the voltage differential V_{m2} required to insure

complete collection of the electron beam by the collector electrode 14 is set forth as follows:

$$V_{m2} = \frac{\epsilon}{2} (d_2 B_2)^2$$

Obviously, if d_1 and d_2 are equal and of sufficient magnitude to insure no arcing, and B_1 is fixed at a suitable value for maintaining the ration E/B_1 to obtain a desired electron velocity and oscillator frequency, B_2 may be varied to provide a suitable value of V_{m2} . This is accomplished by employing any number of properly shaped and orientated magnetic shielding pieces such as 22 and 23 to shield region two of the space 17. The shape of the pieces 22 and 23, the number of such pieces and their orientations may all be varied to achieve the proper amount of shielding so as to provide a suitable magnetic field B_1 in region two of the space. It has been found advisable to maintain the dimension "1" of magnetic pieces 22 and 23 greater than πd_2 . It is also preferable that the ratio of B_2/B_1 be less than one third to insure substantially complete beam collection by electrode 14.

Turning next to FIG. 3 and FIG. 4 there are shown cross sectional views of an M-type backward wave oscillator having a circular interelectrode space 24 and incorporating features of the present invention. FIG. 3 shows a top sectional view BB in which appears a ring shaped sole 25 concentric with a ring shaped slow wave propagating structure 26. Structure 26 might, for example, be comprised of two sets of fingers 27 and 28 interlaced and held in place by fastening rings 27a and 28a, from which the fingers project, to conductive cylinder 29; thereby, forming a tortuous path for slow wave propagation. Such a structure is described in considerable detail in Patent No. 2,890,372, issued June 5, 1959, to E. C. Dench, and entitled "Travelling Wave Amplifiers."

Sole 25 might, for example, have a channel-like cross sectional shape as shown in FIG. 4. Sole 25 and slow wave structure 26 are disposed concentric with each other so as to provide interelectrode space 24 therebetween. A cathode 30 and accelerator electrode 31 are inserted between the open ends of the ring formed by sole 25 and encloses a heater element 32. Electrical leads run from cathode 30, electrode 31, element 32 and sole 25 to conductors 33, 34, 35 and 36, respectively, at the center of the device.

Structure 26 also forms an open ring, the opening therein being partially opposite the opening in the ring formed by sole 25 and collector electrode 37 is inserted in this opening. Electrode 37 may be electrically coupled to the structure to form one end of interelectrode space 24 referred to as region two in the straight line device of FIG. 2.

In operation, a magnetic field from magnet 38 is applied to interelectrode space 24 so that electrons emitted from cathode 30 enter the space and move in a substantially circular path around the space in a counter-clockwise direction, as shown by the arrow on beam 39, giving up energy to the RF wave propagated in structure 26. As the electrons move through space 24 as a beam and approach collector electrode 37, the beam disperses, electrons therein moving to higher potential lines and, thus, moving closer to the fingers of structure 26. By proper orientation of the magnetic shielding pieces 40 and 41 fixed to sole 25 and collector 37, respectively, and adjustment of the strength of magnet 38, substantially complete collection of the beam by collector electrode 37 can be achieved while at the same time maintaining a desired radio frequency output from the device. Such an output might, for example, be taken from finger 42 by coupling to coaxial conductor 43 as shown.

In FIG. 4 there is shown cross sectional view AA taken through the magnetic shielding pieces 40 and 41 and the center of the device. In this view a suitable shape for magnet 38 is shown. The field from the poles of magnet 38 is conducted through magnetically permeable rings 44

and 45. Consequently, the magnetic flux lines travel from ring 44 to 45 through the interelectrode space 26.

The magnetic shielding pieces 40 and 41 are preferably located with a major dimension parallel to this magnetic field. One piece might, for example, be mounted inside the ring of sole 25 as shown and another might, for example, be located between collector electrode 37 and conductive ring 29 as shown in FIG. 4. The shape and orientation of parts forming structure 26 are more clearly shown in FIG. 4, while the location of the fingers are more apparent in FIG. 3. Rings 27a and 28a supporting these fingers are suitably fastened to conductive ring 29 to form the complete slow wave structure 26. The fastening may, for example, be accomplished as shown in the referenced patent.

Upper and lower cover plates 46 and 47 are provided for enclosing the structure 26, interelectrode space 24, sole 25 and cathode 30 so as to form a vacuum seal with conductive ring 29. Electrical conductors 33, 34, 35 and 36 are brought out through terminals 48, 49, 50 and 51 in a suitable electrical feed through 52, which forms a vacuum seal with upper plate 46 and suitable potentials are applied to these terminals for heating cathode 30, accelerating electrons emitted therefrom and providing a uniform electrical field within space 24 while the other parts of the device including upper and lower plates 46 and 47, collector electrode 37 and interdigital delay line 26 are placed at ground potential.

10 or placed at ground potential.

While the present invention is described herein with reference to a symbolic representation of an M-type backward wave oscillator and with respect to a more specific embodiment of such an oscillator including a circular interelectrode space for insuring substantially complete beam collection by a collector electrode, it is to be understood that the spirit and scope of the present invention may be incorporated in other type travelling wave devices to achieve substantially the same or similar results without deviating from said spirit or scope as expressed in the following claims.

40 What is claimed is:

1. An electron discharge device comprising slow wave propagating means at one potential, an elongated electrode at another potential disposed with relation to said propagating means forming an elongated space and bounding an electric field within said space, electron emitting means at one end of said space, electron collecting means at the other end of said space and means producing a transverse magnetic field in said space substantially uniform throughout and means at the end of said space for substantially altering said magnetic field in the vicinity of said collecting means to thereby insure collection of a substantial part of said beam by said collecting means.

2. An electron discharge device comprising slow wave propagating means at one potential, an elongated conductor at another potential disposed with respect to said propagating means to form an elongated interelectrode space having a substantially uniform electric field within, electron emitting means at one end of said space, electron collecting means at the other end of said space and means producing a uniform magnetic field in said space substantially perpendicular to said uniform electric field and also perpendicular to the general movement of electrons within said space and means at the end of said space for substantially altering said magnetic field in the vicinity of said collecting means to thereby insure collection of a substantial part of said beam by said collecting

means,

3. An electron discharge device comprising slow wave propagating means at one potential, an elongated conductor at another potential disposed with respect to said propagating means to form an elongated interelectrode space having a substantially uniform electric field within, electron emitting means at one end of said space, electron collecting means at the other end of said space, means producing a magnetic field in said space substantially

perpendicular to said electric field and also perpendicular to the general movement of electrons within said space and means for magnetically shielding a part of said space in the vicinity of said electron collecting means to thereby insure collection of a substantial part of said beam by said collecting means.

4. An electron discharge device comprising means for propagating an electrical wave in a delay structure, a conductor displaced from said structure forming an inter-electrode space therebetween, means producing substantially crossed electric and magnetic fields within said space, means emitting electrons at one end of said space, means collecting electrons at the other end of said space and means at said other end for reducing the magnitude of said magnetic field in the vicinity of said electron collector to thereby insure collection of a substantial part of said beam by said collecting means.

5. An electrical discharge device comprising slow wave propagating means and conducting means having substantially elongated shapes and disposed with respect to each other to form an elongated interelectrode space, means emitting a beam of electrons at one end of said space, means contiguous with said propagating means disposed at the other end of said space for collecting electrons, means producing crossed electric and magnetic fields in said space and means disposed about said other end of said space for magnetically shielding said space in the

vicinity of said collecting means to thereby insure collection of a substantial part of said beam by said collecting means.

6. An M-type backward wave oscillator including a slow wave structure, a sole electrode forming an elongated interelectrode space with said structure, an electron gun at one end of said space, an electron collector at the other end of said space, means applying potentials to said structure, sole, gun and collector to induce an electric field within said space, means producing a magnetic field substantially perpendicular to said electric field and the general movement of electrons within said space and means magnetically shielding a part of said space in the vicinity of said electron collector to thereby insure collection of a substantial part of said beam by said collecting means.
